ROWING MACHINE

Alexander F. Jackson, East Orange, N. J.

Application February 28, 1946, Serial No. 650,817

3 Claims. (Cl. 272—72)

1

This invention relates in general to exercising apparatus and in particular to exercising apparatus of the rowing-machine type.

One object of my invention is to provide a machine which will in operation simulate the action characterizing actual rowing so that the operator is enabled to secure all of the benefits incident to rowing a racing shell or scull.

Another object is to provide a machine of this character with an operating handle or lever and novel and improved means for providing resistance to movement of the lever in both the pull stroke and the recovery stroke.

Another object is to provide means for regulating the resistance on both the rearward and forward strokes to suit persons of varying muscular strength.

Another object is to provide a machine of this character which shall include novel and improved means for adjusting it to suit persons of different stature.

Another object is to provide a machine of the character described having a base, a handle bar and foot rest mounted thereon, and means for adjustably positioning the handle or lever to adapt the device to the length of the arms and legs of the operator.

Another object is to provide a machine of the character described which shall include a base, and a novel and improved construction and combination of a friction drum, a flexible friction band slidably circumferentially of the drum, and a handle or lever connected to said friction band whereby said band will be caused to frictionally engage said drum and provide a determined amount of resistance to swinging of said lever in both the pull stroke and the push stroke.

Another object is to provide a machine of this character embodying novel and improved features of construction such that it is low enough to be shoved under an article of furniture in the home, and is light and compact enough to be stood on end in a closet or in a corner of a room.

Another object is to provide a machine of this kind that may readily be disassembled and folded into compact form for transportation.

Further objects of the invention are to provide a machine of this character that is simple and rugged in construction, inexpensive to manufacture, reliable, highly efficient and noiseless in operation.

Other objects, advantages and results of this invention will appear from the following description in conjunction with the accompanying drawings, in which

2

Figure 1 is a top plan view of an exercising machine embodying my invention;

Figure 2 is a side elevational view thereof showing the operating lever near its forward position in full lines and near its rearward position in dot and dash lines;

Figure 3 is a sectional view taken on the plane of the line 3—3 of Figure 2;

Figure 4 is an enlarged fragmentary side elevational view of the friction unit showing the operating lever at the start of its rearward or pull-stroke;

Figure 5 is a sectional view of the parts shown in Figure 4 at the end of the forward or push-stroke;

Figure 6 is a view similar to Figure 5 but showing the operating lever near the end of its rearward or pull-stroke;

Figures 7, 8 and 9 are views similar to Figures 4, 5 and 6, respectively, but showing the parts adjusted for reducing the frictional resistance during the forward or push-stroke;

Figure 10 is a cross-sectional view taken on the plane of the line 10—10 of Figure 5;

Figure 11 is a cross-sectional view taken on the plane of the line 11—11 of Figure 5;

Figure 12 is a detail view showing the connection between the outer metallic strip and the lever;

Figure 13 is a detail view partly in elevation and partly in section of a modified form of sliding seat, and

Figure 14 is an end view thereof.

Referring to the drawings in detail, my improved machine comprises a sectional base board formed of a front section 1 and a rear section 2. The sections are joined together by a lower U-shaped clamping plate 3 and an upper clamping plate 4, both plates overlapping the meeting edges of the sections. The upper plate is fastened to the sections by means of fastening members 5, and the sections may be easily disassembled by removing the fastening members from the rear section. The base is supported at its front end on spherical casters 6 to permit it to be readily pushed around on a floor, and at its rear end on a friction pad 7 to keep the machine from slipping when in use. The casters and pad project only slightly below the under surface of the base board so that it rests close to the floor. An inclined foot rest or board 8 is firmly mounted on the front of the base board by means of bolts 9 extending through a vertically disposed front brace member 10 providing a solid flat foundation at its end for supporting the machine in an upright

position when not in use. The foot rest is provided with a strap 11 having openings 12 to permit a single adjustment for both feet and for various size feet. Parallel grooves 13 on the upper surface of the base provide a trackway or guideway for the wheels 14 of a sliding seat 15. While the base, foot rest and seat are preferably made of wood, they may of course be made of any other suitable material and may be made to harmonize with the surrounding furniture in the home.

An important feature of my invention is the provision of a friction unit for providing resistance to the forward (push) and rearward (pull) movements of an operating lever or handle 16. This unit comprises a U-shaped bracket 17 fastened to the front section of the base by means of bolts 18 passing through openings 19 in the section. The openings are aligned and equally spaced to permit adjustment of the bracket along the base to provide leg length adjustment. Secured to the inner surfaces of the upstanding side walls 20 of the bracket is a circular tubular drum 21, preferably by welding its edges of said side walls thereby securing the bracket to the drum. Encircling the drum is a flexible friction band which comprises a strip 22 of a brake lining or leather secured to an outer strip 23 of thin metal. Secured to one end of the band by means of fastening members 24 passing through the strips 22 and 23 is a relatively rigid friction shoe member or band 25. This shoe member is formed with a looped portion 26 forming a bearing for a shaft 27 for securing said end of the friction band to the inner end of the lever or handle 16. At the other end of the friction band, the outer strip 23 terminates in a looped portion 28 forming a bearing for a cross pin 29. The looped portion has a central cut-away portion 30 to permit a threaded eye-bolt 31 to be mounted on the pin for adjustably connecting this end of the band to the lever by means of a thumb nut 32.

The lever 16 is U-shaped in cross-section with its inner end disposed at such an angle to the remainder of the lever that when the lever is at the start of its pull-stroke the first movement rearwardly is to close the heel of the lever 16 onto the shoe 25, thus causing the friction band to tighten upon the drum. At their inner ends, the side walls 33 of the lever straddle the drum 21 and the top surface thereof at this point is shaped to conform to and engage the upper surface of the friction shoe 25.

Extending between the inner straddling portions of the side walls of the lever is a cylinder 35 which is rotatably and eccentrically supported on a screw threaded shaft 36 supported by the side walls. The end faces of the cylinder are serrated or roughened as at 37 for tightly engaging the inner surfaces of the side walls when a wing nut 38 on the outer end of the shaft is tightened. Loosely mounted on the cylinder is a pair of rollers 39, the inner adjacent ends thereof being slightly spaced apart to permit insertion of a pin 40 or the like into an opening 41 in the cylinder for rotating said cylinder on its shaft 36.

The outer end of the lever is formed with spaced pairs of grooves 42 in the edges of the side walls and with an opening 43 in the center of the top portion of the lever in alignment with each pair of grooves for receiving a bolt 44 for fastening a handle bar 45 to the outer end of the lever. The handle bar may be moved along and secured in any pair of aligned grooves to suit the stature of any person using the machine.

In using the machine, the operator moves the seat to its forward position as shown in Figures 1 and 2 and sitting on it, with his legs straddling the drum and his feet beneath the strap 11, grasps the handle bar with both hands, the lever being in the forward position as shown in Figure 2. The handle bar is pulled rearwardly and upwardly in an arc and at the same time pressure is exerted on the foot rest which will move the seat with the operator rearwardly along the trackway. During this action, the inner end of the lever abuts against the outer surface of the friction shoe 25 as indicated at 34, and the friction band will be pulled tightly around the drum 21 by the upward and rearwardly swinging movement of the lever through the eye-bolt 31 thereby creating strong resistance to the swinging of said lever rearwardly.

After the lever has been swung to its furthermost limit rearwardly as shown in Figures 2 and 6, it is pushed forwardly by the operator and at the same time his body is pulled forward with the seat by pulling with his feet on the strap 11. During this pushing action, the rollers 39 of the cylinder 35 engage the inner surface of the drum and the lever presses on the friction shoe 25 at the pivot 27. At the same time, the end of the band connected to the eye-bolt 31 will be released. Accordingly, there will be frictional resistance to the forward movement of the lever of considerably less degree than that encountered on the rearward movement of the lever, the friction being produced between the drum and the friction band in the zone between the cylinder 35 and the point of engagement of the lever with said friction band. Thus work is required to move the lever in either direction.

Adjustment of the resistance during the rearward stroke is obtained by loosening or tightening the thumb nut on the eye-bolt. In order to adjust the resistance during the forward stroke, the wing nut 38 is loosened and the cylinder 35 is rotated on its shaft 36 by means of the pin 40. This swings the cylinder with its rollers 39 toward or away from the inner surface of the drum 21 as shown in Figures 7 to 9, inclusive, and then the wing nut is tightened. Movement of the cylinder toward or away from the inner surface of the drum will increase or decrease, respectively, the frictional resistance during the push stroke of the lever. When adjustment to resistance in both directions is effected, the ratio between the resistance to the forward or push movement and the resistance to the rearward or pull movement will remain constant.

In Figures 13 and 14 is shown a modified form of sliding seat 46 having runners 47 in place of wheels, the runners sliding in grooves 48 in the base. The runners may be secured to the seat by means of screws 49, the screw heads being counter-sunk to provide pockets 50 for receiving a quantity of lubricating material such as wax for lubricating the runners and the grooves to facilitate movement of the seat.

Changes in details might be made without departing from the scope and principle of the invention and I desire to be limited only by the state of the prior art and the appended claims.

What I claim is:

1. An exercising apparatus including a base, a lever, a friction unit mounted on said base comprising a drum having inner and outer concentric surfaces, a flexible friction band slidably partially encircling the outer surface of said drum and having one end pivotally connected to said

lever near one end thereof and its other end connected to said lever nearer the other end of the lever, the first-mentioned end of said lever being arranged to abuttingly fulcrum upon said friction band as the lever is swung in one direction so as to tighten said friction band and produce a predetermined amount of friction between the band and the drum, said end of the lever moving out of contact with and relieving the tension upon said friction band upon swinging of the lever in the opposite direction, and means on said lever between its first mentioned end and said pivotal connection thereof to said friction band to contact and to move along the inner surface on said drum as the lever is swung in the second mentioned direction, whereby a different amount of friction is produced on swinging of the lever in the second direction than on swinging of the lever in the other direction.

2. An exercising apparatus including a base, a lever, a friction unit mounted on said base comprising a drum having inner and outer concentric surfaces, a flexible friction band slidably partially encircling the outer surface of said drum and having one end pivotally connected to said lever near one end thereof and its other end connected to said lever nearer the other end of the lever, the first-mentioned end of said lever being arranged to abuttingly fulcrum upon said friction band as the lever is swung in one direction so as to tighten said friction band and produce a predetermined amount of friction between the band and the drum, said end of the lever moving out of contact with and relieving the tension upon said friction band upon swinging of the lever in the opposite direction, and a roller eccentrically

mounted and adjustable on said lever between its first-mentioned end and said pivotal connection thereof to said friction band to roll along the inner surface of said drum as the lever is swung in the second-mentioned direction whereby a predetermined but constant amount of friction is produced on swinging of the lever in the second-mentioned direction and can be varied by adjustment of said eccentric mounting of said roller.

- 5 10 3. The exercising machine as defined in claim 1 wherein said lever is channel-shaped and straddles said drum, the first-mentioned end of said friction band is connected to the lever between the side walls of the channel and the last-
 15 15 named means includes a cylinder mounted in and between the said side walls of the channel at the inside of said drum to rotate eccentrically, a roller rotatable on said cylinder to contact with the inner surface of said drum whereby upon rotation
 20 20 of said cylinder said roller can be moved near to or farther from the inner surface of said drum, and means for releasably holding said cylinder in adjusted positions.

ALEXANDER F. JACKSON.
